UNITED STATES PATENT OFFICE.

HENRY BAETZ, OF ST. LOUIS, MISSOURI.

DRYING APPARATUS.

Application filed September 25, 1922. Serial No. 590,477.

To all whom it may concern:

Be it known that I, HENRY BAETZ, a citizen of the United States, residing at St. Louis, State of Missouri, have invented certain new and useful Improvements in Drying Apparatus, of which the following is a specification.

My invention has relation to improvements in drying apparatus and consists in the novel features of construction more fully set forth in the specification and pointed out in the claims.

It is generally understood that, in various drying apparatus wherein the material to be dried is fed through a chamber equipped with heating coils or supplied with a blast of heated air, the moisture given off by the material must pass through the casing and necessarily retards the drying operation. Then too, as far as I am aware, there is no provision made for controlling the moisture content of the drying air or the temperature of the casing so as to obtain the most suitable drying conditions for different materials.

It is the object of the present invention to provide a drying apparatus wherein both the moisture content of the drying air and the temperature within the chamber may be controlled throughout the entire extent of said chamber. It is a further object of this invention to provide a drying apparatus wherein different drying conditions can be effected in different parts of the drying chamber. For instance, if in drying a certain material the best results are obtained by subjecting the material first to a comparatively moist circulation of air and then gradually increasing the temperature and decreasing the humidity thereof, these conditions can be effected in the drying chamber and varied at will. This is best accomplished by providing a drying chamber through which the material is fed, said chamber being composed of sections each of which has an independently controlled heater and air circulation, the material being fed progressively from section to section until the drying operation is completed. The moisture laden air may be continuously expelled from each section without having to pass through any other section, which greatly increases the drying efficiency of the apparatus. A further object is to provide a drying apparatus in which the air circulation is transverse to the direction of travel

of the material being dried. Further and other advantages will be better apparent from a detailed description of the invention in connection with the accompanying drawings, in which—

Figure 1 is a combined side elevation and longitudinal section through the drier, the middle part of the same being broken away; Fig. 2 is a top plan of the drier; Fig. 3 is a horizontal section through the drier taken on the line 3—3 of Fig. 1; Fig. 4 is an enlarged vertical cross-section through the drier taken on the zig-zag line 4—4 of Fig. 2; Fig. 5 is an enlarged side elevation of a section of the drier with part of the flue broken away; and Fig. 6 is an enlarged sectional detail taken on the line 6—6 of Fig. 5; and Fig. 7 is an enlarged detail view of part of one of the fresh air dampers showing the quadrant and bolt for holding the dampers in place in front elevation.

Referring to the drawings, H represents a suitable casing which houses the drying chamber C, said chamber being divided into sections S, S', S'', S''', etc., each of which comprises a heating compartment 1, and an air circulation compartment 2, said compartments being formed by a horizontal partition member 3 extending longitudinally throughout the casing, and disposed about one-fourth the height of the casing from the top, and by vertical partition walls 4 extending from side to side of the casing and from the top wall to the partition member 3. Thus the compartments 1 are completely separated from each other, while the compartments 2 are separate compartments only in the sense that each has its own air circulation (about to appear) said compartments 2 being in free communication with each other throughout the length of the drying chamber C to permit the continuous travel of trucks T therethrough, on rails R, said trucks being loaded with the material m to be dried. In each compartment 1 to one side of the middle is a bank of steam coils 5, said coils completely filling about one-fourth of the compartment, and two fan casings 6, 6 are located in the compartment between the inner row of coils 5 and adjacent casing wall. A multi-vaned fan 7 is mounted in each casing 6 on a shaft 8 extending lengthwise throughout the chamber C. The end walls of each fan casing are provided with air intake openings 9, 9 and the peripheral wall of each casing is provided with an air

outlet opening 10, it being understood that the partition 3 is cut out opposite each opening 10 to permit the air from the fan to pass into the compartment 2. The partition wall 5 3 is also provided with openings 11 between compartments 1 and 2, said openings being on the side of the sections S, S', S'', etc. opposite to the fan 7. It will be observed that the fans 7 are disposed on opposite sides of 10 adjacent sections S, S', consequently there is a shaft 8 extending throughout the length of the chamber on each side thereof. The sections S, S' are reversed in other particulars also, the openings 11 being in staggered 15 relation throughout the chamber as well as the heating elements 5. The object of thus reversing the adjacent sections of the chamber is to cause the air circulated through the drying compartments 2, 2, to travel in opposite directions, so that all parts of the 20 stock or material *m* will be exposed to the drying air a maximum period of time. It is readily apparent that if the fan in section S (Fig. 4) is revolved in the direction 25 of the arrow it will cause a circulation of air downward into compartment 2, where the air will encounter a series of deflectors 12, 12, 12, and be directed across the compartment in substantially horizontal paths 30 (see arrows) to the opposite side thereof, when it will be drawn up through opening 11 under influence of the fan intake and through compartment 1 past the heating coils 5 and into the fan, when it is again 35 directed into compartment 2. Thus a continuous circulation of air is created in a closed circuit through compartments 1 and 2. Now the fans in the next adjacent section S' will be revolved in an opposite direction 40 to that in the section just referred to, so that they will create an air circulation opposite to that in section S. The material *m* will thus be subjected to the drying effect 45 of the heated air on one side in section S, and as the material is fed on into section S' it will encounter an air circulation directed against it from the opposite side, and so on throughout the drying chamber.

It is obvious that after the air has circulated 50 in this short circuit through compartments 1 and 2, it will become moisture laden from taking up the moisture in the stock, and some means must be provided for expelling the saturated air and taking fresh 55 comparatively dry air into the respective sections. This is accomplished in the following manner. On the outside of each section S, S', S'', etc., is a flue 13, said flue being on the side of the section where the air 60 passes from compartment 2 to compartment 1, and communicating with the bottom of compartment 2 through an opening 14. Each compartment 1 is provided with air intake openings 15, 15 located on both sides 65 of the flue and a shaft 16 is mounted on the

wall of compartment 1 in bearings 17, 17, said shaft being disposed contiguous to the upper edge of each opening 15 and passing through the flue 13, the shaft having a flue damper 18 mounted on it inside the flue, 70 and a damper 19 opposite each opening 15. The dampers 19, 19 are disposed at right angles to damper 18, so that when damper 18 is across the flue 13 to close same, the dampers 19 will be in front of openings 15 75 to close these openings. Thus the air intake openings 15, 15 are controlled simultaneously with the air discharge through the flue, the one being opened or closed in proportion as the other is closed or opened. 80 One of the bearings 17 has a quadrant 20 formed with it, said quadrant being provided with a plurality of openings 21, and a bolt 22 is mounted on the adjacent damper 19, said bolt being adapted to enter any one 85 of the openings 21 according to the amount it is desired to open the dampers. Since the dampers 18 and 19 of each section S, S', etc. are controlled independent of any other section, it is possible to obtain varying 90 conditions of humidity in the respective sections by varying the positions of these dampers so as to admit variable quantities of 95 fresh air to compartment 1 of each section. Obviously, the more fresh air that is admitted to any given section the more spent, moisture laden air will be expelled. Some 100 materials require rather exacting drying conditions, and in order to exercise perfect control over the drying conditions I may place a hygrometer 25 in each flue 13 above the damper 18, and by noting from time to time the moisture content of the air being expelled through the flue the operator will know whether to increase or decrease the 105 amount of fresh air admitted to the compartment 1.

In order that the hygrometer 25 may be read from the outside of the flue, the latter may be provided with window 26 on its 110 outside wall.

The shafts 8, 8 each carry a pulley 27 on one end, the pulleys 27 being connected by a crossed belt 28, and one of the shafts 8 carries a driving pulley 29 on its other end, so that the shafts 8 (and, of course, the fans 7 mounted on the shafts) will be simultaneously driven in opposite directions. Obviously other driving means for the shafts 115 may be resorted to if desired.

The casing C is provided with doors D, D, at each end through which the material is fed to the casing and discharged therefrom.

The supply of steam to each heating coil 5 125 is controlled by a valve *v*, and a main valve *V* controls the supply of steam to the entire battery of coils.

Having described my invention, I claim:

1. A drier comprising a suitable casing 130

or chamber, said chamber being divided longitudinally into a series of juxtaposed sections, each of said sections being divided into a fan compartment and a drying compartment in superposed relation, a fan in each fan compartment operating to circulate air through the drying compartment of the section, and means for causing the air to circulate through the drying compartment in substantially horizontal paths.

5 2. A drier comprising a suitable casing or chamber, a succession of air moving and air heating devices disposed in the upper part of said chamber and operating to circulate heated air across the chamber laterally in opposite directions.

10 3. A drier comprising a suitable casing or chamber, said chamber being divided longitudinally into a series of juxtaposed sections, each of said sections being divided into a heating compartment and a drying compartment, an air moving and an air heating device in each heating compartment operating to circulate heated air through the drying compartment of the section, and means for causing the air to circulate through the drying compartment in substantially horizontal paths.

15 4. A drier comprising a suitable casing or chamber, said chamber being divided into a heating compartment and a drying compartment, means for effecting a continuous circulation of air through said compartments, said chamber being provided with an air inlet and an air outlet, and means for simultaneously controlling the volume of air admitted to the chamber and the volume discharged therefrom.

20 5. A drier comprising a suitable casing or chamber, said chamber being divided into a heating compartment and a drying compartment, means for effecting a continuous circulation of air through said compartments in a path lying wholly within the chamber, means for effecting and controlling a discharge of air from the chamber in a path parallel with the circulation path and simultaneously therewith controlling the influx of fresh air to the chamber.

25 6. A drying apparatus comprising a suit-

able casing or chamber, said chamber being divided into a heating compartment and a drying compartment, a heating element and a fan in the heating compartment to one side thereof, said fan having an intake communicating with the heating compartment and an outlet communicating with the drying compartment at one side thereof, the heating and drying compartments being in communication on the side opposite to the fan 55 outlet, a series of deflectors for causing the air to circulate through the drying compartment in substantially horizontal paths, a flue disposed on the outside of the casing on the opposite side from the fan, the bottom of said flue communicating with the drying compartment, the heating compartment having a fresh air intake adjacent said flue, and operatively associated dampers for controlling the supply of air to the fresh air intake and 60 discharge of air from said flue.

7. The method of drying materials which consists in successively subjecting the material to a series of independent heated air circulations, and independently regulating 75 the humidity of the air in said circulations by fresh influxes of comparatively dry air under control.

8. The method of drying materials which consists in successively subjecting the material to a series of independent heated air circulations alternately directed in opposite directions, and independently regulating the humidity of the air in said circulations by fresh influxes of comparatively dry air under 80 control.

9. A drier comprising a suitable casing, said casing being divided longitudinally into a series of communicating juxtaposed sections, each of said sections being divided 90 into a heating compartment and a drying compartment, means for effecting a continuous circulation of air through the compartments of each section, and means for independently controlling the volume of air 95 to each section and the volume of air discharged therefrom.

In testimony whereof I hereunto affix my signature.

HENRY BAETZ.
